UNITED STATES PATENT OFFICE

2,506,748

THERMOSTATIC SWITCH

Joseph P. Stefan, Park, Kans.

Application October 15, 1947, Serial No. 779,852

1 Claim. (Cl. 200—140)

1 This invention relates generally to poultry brooders, and more particularly to a temperature alarm and correction system, adapted to provide a signal when the temperature rises or falls beyond predetermined high and low limits, and to energize a heating unit when the temperature falls below the low limit, the device including a specially designed snap switch construction embodied in the electrical switches used in the system.

A primary object of this invention is, therefore, to provide signal and control means whereby the operator of poultry brooder equipment may better control the temperature of the brooder equipment, it being understood that this invention is primarily designed for use as an auxiliary unit for use with regular thermostatic control and heating equipment for the brooder, although this equipment slightly modified may, if desired, be used as a primary or sole heat control unit.

Another salient object of this invention is to provide means of this character with novel switch devices of very simple form and designed to provide a type of snap action particularly acceptable for use with this system.

Still another more specific object is to provide a switch construction in which the closing and opening of the switch is characterized by a strong snap action and in which the switch contacts will remain closed pending a wide variation in temperature after once being closed.

And a last object to be specifically mentioned is to provide a device of this character which is relatively inexpensive and practicable to manufacture, extremely simple to install and convenient to use, and which will give generally efficient and durable service.

With these objects definitely in view, together with other objects which will appear as this description proceeds, this invention resides in certain novel features of construction, combination and arrangement of parts and portions as will be hereinafter described in detail in the specification, particularly pointed out in the appended claim, and illustrated in the accompanying drawings which form a material part of this application and in which:

Figure 1 is a somewhat diagrammatic view of the different units in this invention operatively connected together.

Figure 2 is an enlarged horizontal sectional view through the casing for the specially designed switch construction, showing the main portions of the switch construction in plan, the view being taken on the line 2—2 in Figure 1;

Figure 3 is a vertical longitudinal sectional view, taken on the line 3—3 in Figure 2;

Figure 4 is an elevational view of a single switch unit, such as that represented in vertical section at the right hand side of Figure 3;

2

Figure 5 is a similar view of the double switch construction; and

Figure 6 is a diagrammatic view showing the electrical connections.

Similar characters of reference designate similar or identical parts and portions throughout the specification and throughout the several views of the drawings.

Referring now to the drawings in detail, it should first be understood that this invention is primarily adapted for use with an environment including a brooder or brooder house having a main thermostatically controlled heating unit, the subject matter of this invention being primarily a signal system to indicate the improper functioning of the main heating and ventilating system, and to provide an auxiliary heating unit system which will be automatically put into operation at the same time as the signal of too low a temperature is given.

The system includes an auxiliary heater 10, an audible signal unit 12, a thermostat unit 14 and control switches 16 and 18 of double and single character, respectively, together with a complement of electrical conduits, an alarm switch 20 and certain other minor features of construction.

The casing 22 is represented as being rectangular in form and is provided with louver openings 24, and simple openings 26, so that the interior of the casing is at all times approximately the same temperature as the brooder or brooder house in which the casing is situated. A pair of bosses 28 and 30 are provided at the ends of the casing. The boss 28 is interiorly threaded to directly receive the adjusting screw 32 and the boss 30 comprises a bearing to receive a projecting boss 44 on a rectangular yoke 42, and an adjusting screw 34 is threaded through the boss 44, these adjusting screws being locked at any predetermined adjustment by wing nuts 36. The thermostat unit 14 is connected to the inner end of the screw 32, by means of a rotating bearing terminal 38, or by any other suitable means, to allow the longitudinal adjustment of the screw 32 for shifting of the thermostat 14 without the rotation of the thermostat. The other side of the thermostat may be rigidly secured to the projecting arm 40 of the rectangular yoke 42. The yoke 42 is shifted by said thermostat and is designed to operate the switches 16 and 18.

The switch 16 is essentially a duplication of the switch 18 which will now be described. This switch includes a housing 50 which is mounted on brackets 52 and the housing is provided with a rigid diaphragm 54. The fixed contact 56 of the switch is secured to this diaphragm 54 and the moving contact 58 of the switch is carried by a lever arm 60 which is pivoted as at 62 on this same diaphragm. The lever arm 60 extends, as

at 64, beyond the pivot 62 and carries a resilient contact bar 66 which is returned to the central portion of the housing 50 and is adapted to be actuated by a push pin 68, this push pin being slidably mounted in the central portion of the wall of the housing 50, and positioned for contact by the portion 82 of the yoke 42 corresponding functionally with the screw 34, it being understood that this yoke 42 encircles the switches 16 and 18. The resilient contact bar 66 is extended beyond its connection with the lever portion 60 and the extending arm 70 must be of magnetic material for coaction with a permanent magnet 72 secured to the casting 50 adjacent the end of the said extending portion 70. Magnetic attraction between the portion 70 and the magnet 72 biases the moving contact 58 toward the fixed contact 56.

It will be apparent from the foregoing, that actuation of the yoke 42 will move the push pin 68 and will force the arm 66 as to the left in Figure 3, to open the switch 18 when the yoke is moved to the direction as to the left in Figure 3. A flexible electrical connection 74 and a lead 76 complete the essential features of this switch construction. The other switch 16, which is represented in Figure 5 will be seen to be a mere duplication of the switch 18, inasmuch as the switch 16 is comprised of two similar units with the spring bars 66 joined by a lever or cross brace 78, the cross brace 78 being actuated by the pin 80 which, in turn, is moved in one direction by the portion 82 of the yoke 42. A single large permanent magnet 84 may be used in place of two smaller magnets 72. For purposes of reference, the two parts of this double switch will be differentiated by the numerals 86 and 88, in Figure 6.

Referring now to Figure 6, it will be seen that the switches 86 and 88 are each connected to one side of the power leads 90, and that these power leads are controlled by a master switch 92. It will also be noted that the same lead as is connected directly to the switches 86 and 88 is also connected by means of the connection 94 to the single switch 18. The Figure 6 represents a condition in which the upper limit of temperature has been reached and the yoke 42 has been moved as to the right in this figure closing the switch 18 and leading power through this switch and through the leads 96, 98 and the switch 20 to the step-down transformer 100 and the return lead 102. The step-down transformer 100 supplies power at proper voltage to the electric bell 12, or other suitable signal. Movement of the yoke 42 in the opposite direction, that is, as to the left in Figure 6 will close the switches 86 and 88 leading power through the leads 106 and 108 to the leads 110 and 112 and energizing the heater 10, while simultaneously energizing the electric bell 12. The operation of this invention has already been described in connection with the description of the mechanical details of construction, and it should now be evident that this invention will accomplish the objects sought to be achieved thereby. In recapitulation, heating of the thermostat unit 14 will cause the yoke to be moved in one direction while chilling of the brooder or brooder house will cause the yoke to be moved in the opposite direction. Normal temperature within the brooder or brooder house will allow all the switches to be in open position.

Overheating of the poultry will be signalled by the actuation of the alarm unit 12 which will ordinarily be placed in the home of the operator or in some other suitable location and it will be obvious that the switch 20 may be used to open this circuit to discontinue the ringing of the bell 12 after the signal has been given. Underheating of the brooder or brooder house will provide a similar signal by closing the switch 86 and will also cause the energization of the heater 10 by closing the switch 88. Since this device is ordinarily used in connection with the rearing of very young chicks, too low a temperature in the brooder or brooder house will quickly cause a high rate of mortality amongst these chicks, and the auxiliary heater 10 has been found to ameliorate the damage caused by failure of the main heating system, when the operator is unable to give absolutely immediate attention to the problem of restoring proper heating facilities. The special construction of the switches has been developed in order that each switch, once closed, will remain closed under the influence of the magnets 72 or 84, even though the yoke 42 may be moved in either direction slightly as by variations of temperature conditions and actual repair or proper adjustment of the main heating system has not been accomplished, the operator being therefore warned of the failure of the heating system even though this failure occurred during his absence and even if this failure is not apparent upon his return, as when weather conditions have changed in the meantime in a manner to make such failure not otherwise easily detectable.

Many minor variations may be made in the structure as disclosed in this application and this invention should be limited only by a proper interpretation of the terminology of the appended claim.

Having described the invention, what is claimed as new is:

A circuit closer for a temperature alarm and correction system comprising a casing, a yoke slidably mounted in said casing, a thermostat wafer unit adjustably mounted in the casing and operatively connected to said yoke, said yoke having a switch operating member fixed on one end of the yoke and an adjustable switch operating member on the opposite end of the yoke, switches mounted on said casing and having contacts individually operated by said switch operating members, whereby the adjustment of the wafer unit adjusts the yoke with reference to both switches and adjustment of said adjustable switch operating member affects the operation of one switch.

JOSEPH P. STEFAN.
